UNITED STATES PATENT OFFICE.

ALBERT GLOOR, OF CHICAGO, ILLINOIS, ASSIGNOR TO SASGEN DERRICK CO., OF CHICAGO, ILLINOIS, A CORPORATION OF ILLINOIS.

TOWING-DERRICK.

1,400,540.

Specification of Letters Patent. Patented Dec. 20, 1921.

Application filed January 20, 1921. Serial No. 438,731.

To all whom it may concern:

Be it known that I, ALBERT GLOOR, a citizen of the United States, and a resident of Chicago, in the county of Cook and State of 5 Illinois, have invented certain new and useful Improvements in a Towing-Derrick, of which the following is a specification.

My invention relates to improvements in derricks and has special reference to improvements in derricks particularly adapted 10 for use upon trucks or automobiles for use in towing cars, or pulling cars out of ditches, etc.

A particular object of my invention is to 15 provide a simple derrick for the use mentioned which shall have a boom which can swing freely around a complete circle; and which boom can be lowered to be aligned with the pull when the device is used to pull 20 cars out of ditches or to pull out the car upon which the device is fixed.

A special feature of my improved derrick 25 is its adaptation to use with an automobile repair truck having side tool boxes on its platform, the boom being pivoted at a point above the tops of the boxes so that it can readily be aligned even over the boxes, with the line of strain.

A further feature of my invention relates 30 to simple means for locking the swinging boom to the standard when the device is used for towing a car. Another feature relates to means for quickly clamping the swinging boom to the standard for preventing 35 the boom swinging around under the ordinary strains of use, or to hold it in position over the car upon which it is mounted when the car is traveling from place to place.

I obtain the complete circle swing of the 40 boom by means of the manner in which I mount the winches or cable drums on the boom itself, thus eliminating any interference with the cables in swinging the boom around and providing a very simple and 45 easily operated device.

My invention will be more readily understood by reference to the accompanying drawings forming part of this specification, and in which:—

50 Figure 1 is a side elevation of an automobile truck equipped with a derrick for hoisting and towing automobiles and embodying my invention;

Fig. 2 is a similar view of the derrick; Fig. 3 is a top plan view of the standard of 55 the derrick;

Fig. 4 is a fragmentary horizontal section on the line 4—4 of Fig. 2;

Fig. 5 is a vertical fragmentary section on the line 5—5 of Fig. 4; 60

Fig. 6 is a horizontal fragmentary section of the standard on the line 6—6 of Figs. 2; and

Fig. 7 is a fragmentary top plan view of 65 the rear portion of the truck body.

For an automobile repair truck it is necessary to provide not only a means for towing a disabled car but also means for pulling the car on to the roadway or turning it over, if necessary, or for pulling the truck itself out 70 of disadvantageous situations such as a ditch alongside of a road.

My invention is embodied in an automobile truck, 1 having a bed or floor 2, at the rear of the cab or driver's position. At the 75 sides of the bed are arranged tool boxes 3 rising above the floor 2 and in which the necessary jacks and other tools may be conveniently carried.

On the bed 2 between the tool boxes 3 is 80 arranged a derrick.

I preferably arranged the derrick at the rear end of the bed, as illustrated in Fig. 1, so that, as shown in dotted lines, the hoisting boom and hook can be swung out to the 85 rear of a truck for towing purposes.

My improved derrick comprises a rigid base 4 made up of two cross pieces 5 and 6 and a central longitudinal piece 7, the cross pieces are long enough so that the ends can 90 be suitably belted to the side members of the chassis through the bed of the body. The rear cross piece 5 is arranged adjacent to the rear end of the bed 2 and the forward cross piece 6 is spaced forwardly therefrom sufficient to give adequate support to the post or standard 8 of the derrick, the forward cross piece providing anchoring connections for suitable inclined braces.

At a point on the standard above the 100 top of the tool boxes 3 I arrange a collar 9. This collar is rotatable around the standard, it rests upon a fixed collar 10 bolted to the standard and to which the upper ends of side braces 11 are secured by 105 removable bolts 12 and the upper ends of

forward and outwardly inclined braces 13 are fixed by a removable bolt 14.

The lower ends of the cross braces are secured to the outer ends of the cross piece 5 in brackets 15 by removable bolts 16 and the lower ends of the forward braces 13 are secured in suitable brackets 17 at the outer end of the forward cross piece 6 by removable bolts 18.

10 The standard is secured in position on the base at the juncture of the rear cross piece 5 and the longitudinal piece 7 in a fixed bracket or plate 19. This bracket 19 consists of a flat plate 20 rigidly secured to 15 the base and having upstanding lugs or projections 21 at its corners between which the base of the standard is received. The standard has a base casting 22 provided with four lugs 23 inside of the several projections 21 and all of these projections are 20 perforated and the standard is secured to the base plate 20 by two transverse bolts 24 which pass through the several perforations at the forward and rear sides of the 25 standard and are suitably removably held in place as by nuts 25.

By removing one or the other of the bolts 25 and disconnecting the several braces from the standard the standard can be swung 30 down on the other bolt 24 as upon a hinge to a horizontal position as indicated in dotted lines in Fig. 2.

When swung down forwardly the standard will lie on the bed of the truck between the tool boxes and the truck can then be used for other purposes, or if desired, the other bolt 25 may also be removed and the derrick entirely removed from the truck.

Upon the collar 9 I pivotally mount the 40 lower end of a boom 26 to swing up and down on the pivot bolt 27. As best shown in Fig. 5, the collar 9 is secured on an upper cylindrical extension of the fixed collar 10, which is provided at its upper end 45 with an external flange 28 forming a circumferential groove 29 in which the collar 9 may be rotated around the standard.

This collar 9 is split at one side as shown at 30 and I provide a clamping lever 31 for 50 closing the collar tightly into the groove 29 upon the fixed collar 10 to prevent the free rotation of the collar and the boom. The boom is held at any suitable inclination by means of a rotatable cap or collar 32 which 55 is mounted on a fixed cap member 33 secured on the top of the standard, which is tubular.

The collar 32 is held in place by a nut 34 screwed upon a central threaded stem 60 35 which is rigid with the standard. Upon the collar is pivotally mounted a yoke 36 comprising side bars 37 between the free ends of which are rotatably secured a pair 65 of sheaves 38. At the outer end of boom

26 which is preferably made up of a pair 65 of channel beams arranged back to back and spaced apart, is mounted a connecting end member 39. In the upper part of this end member a sheave pulley 40 is rotatably mounted. In the lower part of this end 70 member is mounted a hoisting sheave 41 and between the outer ends of the channel beams and adjacent to the end connections, I provide a pair of sheaves 42 rotatably mounted on a transverse bearing member 43. 75

At the base of the boom I arranged two independent winches, 44 and 45 having suitable gearing and drums.

The winch 44 is adapted to control a cable 46 which leads over one of the guide 80 sheaves 42 and down to a hoisting device 47 suspended from the outer end of the boom. In the form shown this hoisting device consists of a hook 48 dependent from a sheave frame 49 in which a cable sheave 85 50 is rotatably mounted and the cable 46 is trained around the sheave 50, then around the sheave 41 at the end of the boom, the end of the cable being secured to the sheave frame 49. 90

The winch 45 carries a cable 51 which is trained around the other of the guide sheaves 42 at the end of the boom and is then led around one of the sheaves 38 at the top of the standard, then back around 95 the guide sheave 40 at the outer end of the boom, then back to the top of the standard around the other guide sheave 38, the end of the cable being finally taken to the end of the boom and secured to the connection 100 39.

By means of the winch 45 and cable 51 I am enabled to set the boom at any desired inclination or elevation and by means of a suitable dog 52 which engages in the 105 teeth of one of the gears of the winch 45 I am enabled to hold the boom as set.

By means of the winch 44 and cable 46 I am enabled to put a pulling strain upon the hook 48 as may be desired, and by means of a suitable dog 53 which engages in the teeth of one of the gears of the winch 44 I am enabled to retain the hook 48 at any set position.

The collars 9 and 32 by which the boom 115 is secured to the standard are both rotatable on the standard and consequently the boom can be swung around bodily with its winches to any desired position and unhindered by braces, guy ropes or any other device. The 120 derrick being arranged as described so that the boom can be swung around bodily through 360 degrees to any desired relative position to the bed of the truck and being capable of being raised and lowered to any 125 desired angle, I am enabled to align the boom with the line of strain on the pulling cable 51; that is that portion of it between the

boom and the hook, especially in pulling the truck itself or another car out of a ditch or for similar work in relation to wrecks, etc.

The clamping device 31 on the collar 9 provides a frictional engagement of the collar 9 on the standard to hold the boom against swinging out of a set position while the truck is run from place to place, but when it is desired to swing the boom around to the rear as shown in dotted lines in Fig. 1 to lift or hold elevated the forward or rear part of a car for towing it, or even just for towing purposes, it is desired to have some more positive means for holding the boom against the side pull of the tow both from swinging and from turning corners. For this purpose I provide coöperating projections 54 and 55 on the collar 9 and on the fixed collar 10 respectively, and having vertical openings adapted to register with each other when the boom is swung around to the rear and which openings are adapted to receive a locking pin when they are in registry. This pin absolutely locks the boom against swinging around on the standard.

When it is desired to lay the standard down as shown in dotted lines in Fig. 2, the boom is first swung around to the rear and is then locked by a pin being placed in the openings in the projections 54 and 55 and then it may be swung down to the rear as the standard is lowered, or it may be positioned up over the driver's seat, as may be desired, or if desired, the standard with the boom may be removed as an entirety from the truck.

As many modifications of my invention will readily suggest themselves to one skilled in the art, I do not limit or confine my invention to the specific structures herein shown and described.

I claim:

1. In a derrick of the kind described, a fixed standard, a collar rotatable thereon between the ends thereof, a boom pivoted at one end to the collar, a cable connecting the free end of the boom to the top of the standard, a winding drum on the boom for said cable for lifting and lowering the boom, a second winding drum on the boom, a cable leading from the second drum to the free end of the boom and adapted to hang from the free end of the boom for connection to an object to be acted upon, and means for locking the collar against rotation on the standard.

2. An automobile repair wagon having side tool boxes on its platform in combination with a derrick fixed upon the platform between the boxes, the derrick comprising a fixed vertical standard, a collar on the standard above the tops of the boxes, a boom pivoted at one end to the collar, a cable connecting the free end of the boom to the top of the standard, a winding drum on the boom for said cable, a second drum on the boom,

a cable wound on the second drum and leading to the free end of the boom, and means carried by the latter cable dependent from the end of the boom for connection to an object to be acted upon, the boom being capable of being swung through 360 degrees and means for locking the boom when at the rear of the standard.

3. In a derrick of the kind described, a non-rotatable standard, a boom, a collar on the standard to which one end of the boom is pivoted for swinging up and down, the collar being held against movement longitudinally of the standard and rotatable thereon, means for clamping the collar upon the standard to prevent rotation thereof, and means for positively locking the collar to the standard in one position.

4. In a derrick of the kind described, a non-rotatable standard, a boom, a split collar on the standard to which one end of the boom is pivoted for swinging up and down, the collar being held against movement longitudinally of the standard and rotatable thereon, an eccentric lever on the collar for clamping the collar to the standard, and positive locking means for holding the boom in one position against swinging around horizontally.

5. In a towing device, a derrick fixed on a car, a fixed vertical standard, a boom, a collar rotatable on the standard between its ends to which one end of the boom is pivotally mounted to swing up and down, means carried by the boom for swinging it up and down and retaining it in its adjusted position, a lifting or pulling cable leading from the free end of the boom, hoisting gear carried by the boom for operating said cable, the boom being adapted to be positioned substantially in the line of strain when an object is being operated upon by said second mentioned cable.

6. In a towing device, a derrick fixed on the rear end of an automotive vehicle and comprising a fixed vertical standard, bracing means connected to the standard above its lower end, a collar rotatable on the standard above the connection with said bracing means, a rotatable member at the top of the standard, a boom pivoted at one end to said collar to swing up and down, a winch on the boom and connected by a cable to said rotatable member at the top of the standard for swinging the boom up and down, a second winch on the boom and a cable leading therefrom to the outer end of the boom and adapted to be connected to an article to be acted upon, the boom being adapted to be rotated around the standard and to be swung up and down to align the boom with the line of strain when the device is used for pulling a car out of a ditch, etc., and means for locking the boom against rotation when the device is used for towing purposes.

7. In a device of the kind described, a derrick fixed on the rear end of an automotive vehicle and comprising a fixed standard, a collar rotatable on the standard between its ends, a boom pivoted at one end to the collar, a rotatable member at the top of the standard, a boom lifting cable connected to said rotatable member leading to the free end of the boom and a winch on the boom on which said cable is adapted to be wound, the collar and the standard having openings adapted to be aligned for receiving a locking pin to hold the boom against swinging around when the device is used for towing a car.

8. The combination with an automotive vehicle of a derrick, means for removably mounting the derrick on the bed of the vehicle, comprising pairs of upstanding spaced

apart, perforated lugs secured to the bed of the vehicle, the lower end of the post or standard of the derrick having perforations registering with the perforations in the upstanding lugs, removable bolts secured in the registering perforations for securing the post in position, a collar fixed on the post above its lower end provided with perforated lugs, upstanding connection plates on the bed of the vehicle, brace members having perforations in their ends adapted to be registered with respective perforations of the collar and said upstanding connection plates and bolts removably secured in said registered perforations for removably securing the braces in position.

Signed at Chicago, Ill., this 7th day of December, 1920.

ALBERT GLOOR.
